UNITED STATES PATENT OFFICE.

GEORGE E. STEENROD, OF FREEPORT, ILLINOIS.

REGULATOR FOR WINDMILLS.

SPECIFICATION forming part of Letters Patent No. 728,513, dated May 19, 1903.

Application filed February 4, 1903. Serial No. 141,938. (No model.)

To all whom it may concern:

Be it known that I, GEORGE E. STEENROD, a citizen of the United States of America, residing at Freeport, in the county of Stephenson and State of Illinois, have invented a certain new and useful Improvement in Regulators for Windmills, of which the following is a specification.

This invention relates, specifically, to an automatic regulator for throwing windmills into and out of gear, according as there be insufficient or sufficient water in the tank thereof; and it consists of certain new and useful features of construction and combinations of parts especially devised to that end, all as hereinafter fully described, and specifically pointed out in the claims.

Referring to the accompanying drawings, which form a part of this specification, Figure 1 is an isometrical view of a windmill-regulator embodying my invention attached to one of the posts of a windmill-tower. Fig. 2 is a front elevation of the regulator with parts broken away. Fig. 3 is a top plan view of the parts shown in Fig. 2. Fig. 4 is a section at the dotted line 4 4 in Fig. 2 of parts there shown. Fig. 5 is a section at the dotted line 5 5 in Fig. 4 of parts there shown. Fig. 6 is a view showing modified means for connecting the float with the windmill-regulator when the tank is at a distance from the tower and should be entirely disregarded, except when reference is being made hereinafter to such modified connecting means.

Like letters of reference indicate corresponding parts throughout the several views.

A is the base-plate of the machine, which has a vertical slideway A' A² therein and is provided with lugs A³ A⁴ A⁵ A⁶ A⁷ A⁸, the uses whereof will be designated hereinafter.

B is a rack having teeth B' extending along one edge thereof and slidably mounted in the slideway A' A² in the base-plate A.

C is a wire connecting the rack B by its upper end with and suspending it from the pull-out mechanism of the windmill mechanism common and very well known in windmill construction.

D is a pump-rod connected above with the crank-pin of a windmill of any ordinary construction and below with a pump D'.

E is a pawl-actuating lever horizontally

mounted between its ends on a pivot-bearing E', inserted through the lug A³ and plate A, and is pivotally connected by one end E² with the pump-rod D.

F is a pawl jointed by means of the pivot F' to the free end E³ of the lever E, so as to freely swing thereon, and adapted to be thrown into and out of engagement with the teeth B' of the rack B.

G is a furcated lever mounted on the same pivot F' as the pawl F, carrying a weight G' at its upper end and having its horizontal furcations G² G³ loosely bestriding the pawl F.

H is a furcated lever mounted on a horizontal stud-pivot H' on the plate A, provided with a horizontal lug H^a and having its vertical furcations H² H³ very loosely bestriding the horizontal furcations of the lever G.

I is a detent mounted on a horizontal stud-pivot I' on the plate A, normally held into engagement with the teeth B' of the rack B by means of the lever-weight I² and adapted to be thrown out of engagement with such rack B by the lug H^a on the lever H.

J is a horizontal tilting-beam rigidly secured at a point preferably about midway between its ends to the lower end portion of the furcated lever H.

K is a tank partly filled with water K'.

L is a float suspended from the end J' of the beam J by means of a wire L'.

M is a weight slidably adjustable along the free end of the beam J and serving to balance the float L in the water K'.

N N' N² are bolts inserted through holes N³ N⁴ N⁵ in lugs A⁴ A⁵ A⁶ on the base-plate A and through corresponding holes in the clip O to rigidly secure the regulator to one of the angle-steel posts P of the tower P'.

Whenever the tank K is at a distance from the tower P', the upper end of the wire L', Fig. 6, is connected with the horizontal arm of a bell-crank L³, mounted on a post L², and a wire L⁴ is extended from the vertical arm of such bell-crank L³ through and fastened in a hole H⁴ in the furcation H².

When the tower is wide or the stroke of the mill is too short, the pivot-bearing E' should be shifted from the position shown in Figs. 2 and 3 to the holes Q Q' Q² in the lug A⁷, lever E, and base-plate A in order to insure the proper working of the regulator.

The drawings show the water-tank filled, the regulator at rest, and the mill held out of gear by the wire C. If now any considerable amount of water be withdrawn from the tank by the drinking of animals or otherwise, the float L will descend and, acting through the beam J, tilt the lever H in the direction indicated by the arrow in Fig. 2 until it strikes and rests against the lug A⁸. The movement of the lever H just described causes the lug H^a thereon to strike and disengage the detent I from the rack B and the furcation H² thereof to strike the furcation G² of the lever G, which in turn strikes and also disengages the pawl F from such rack B, thereby releasing the latter and through it the wind-wheel of the mill, which will then go into operation and pump water until the float L rises sufficiently to be overbalanced by the weight M, which will thereupon tilt the beam J in the opposite direction and, acting through the furcated levers G H, throw the pawl F into engagement with the rack B and also permit the weight I² to throw its detent I into engagement therewith. The mill will then continue to operate the pump and through its rod D oscillate the lever E until the pawl F thereon has driven the rack B downward in its sideways A' A² in the base-plate A until the mill is again pulled out of gear by the wire C.

The joint operation of the weighted furcated lever G and the furcated lever H is to cause the pawl F and detent I to swiftly and surely engage with and disengage from the rack B at the proper times.

What I claim as new, and desire to secure by Letters Patent, is—

1. In a regulator for windmills, in combination, a base-plate having a rack-slideway therein, a rack slidable in such slideway, a pawl-actuating lever pivotally mounted on the base-plate, a pawl mounted on a pivot on the pawl-actuating lever and adapted to be thrown into and out of engagement with the rack, a furcated lever—mounted on the same pivot as the pawl-actuating lever—carrying a weight, at its upper end, and having its horizontal furcations loosely beshring the pawl, a detent, mounted on a pivot, on the base-plate, and normally held into engagement,

with the rack, by means of a lever-weight, a furcated lever—mounted on a pivot on the base-plate—provided with a lug, adapted to throw the detent out of engagement with the rack, and having its vertical furcations very loosely beshring the horizontal furcations of the weighted furcated lever, and means for tilting the lever, having vertical furcations, back and forth, substantially as and for the purpose specified.

2. In a regulator for windmills, in combination, a base-plate having a rack-slideway therein, a rack slidable in such slideway, a pawl-actuating lever pivotally mounted on the base-plate, a pawl mounted on a pivot on the pawl-actuating lever and adapted to be thrown into and out of engagement with the rack, a furcated lever—mounted on the same pivot as the pawl-actuating lever—carrying a weight, at its upper end, and having its horizontal furcations loosely beshring the pawl, a detent, mounted on a pivot, on the base-plate, and normally held into engagement with the rack, by means of a lever-weight, a furcated lever—mounted on a pivot on the base-plate—provided with a lug, adapted to throw the detent out of engagement with the rack, and having its vertical furcations very loosely beshring the horizontal furcations of the weighted furcated lever, and a tilting-beam secured, between its ends, to the lever having vertical furcations, substantially as and for the purpose specified.

3. In combination, a windmill-tower post of angle form in cross-section, a windmill-regulator base-plate, provided with connecting-lugs having bolt-holes extending therethrough, a clip O having bolt-holes therein, and bolts N N' N², inserted through and secured in the holes in the lugs in the base-plate and clip, to secure such base-plate to a tower-post of the form indicated, substantially as and for the purpose set forth.

In testimony whereof I have signed my name to this specification in the presence of two subscribing witnesses.

GEORGE E. STEENROD.
